E. N. Gelston
His Attorney.

UNITED STATES PATENT OFFICE.

ALFRED GILBERT BROWN, OF EGAN, DAKOTA TERRITORY.

DRAFT-EQUALIZER.

SPECIFICATION forming part of Letters Patent No. 403,873, dated May 21, 1889.

Application filed January 3, 1889. Serial No. 295,299. (No model.)

To all whom it may concern:

Be it known that I, ALFRED GILBERT BROWN, a citizen of the United States, residing at Egan, in the county of Moody and Territory of Dakota, have invented certain new and useful Improvements in the Method of and Apparatus for Equalizing Draft; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to an improved method of and apparatus for equalizing draft, whereby an effective equalization of the traction is produced where the power is unequally divided on the respective side of the vehicle pole or shaft; and it consists in the method and arrangement of parts hereinafter described, and definitely pointed out in the claims.

25 The object of my invention is to provide a simple, effective, and convenient means for equalizing draft and distributing the stress on the several members of the attached portions of the vehicle. I attain this object by the device and construction illustrated in the accompanying drawings, wherein like letters of reference indicate corresponding parts in both views, and in which—

Figure 1 represents a plan view of my equalizer as attached to a vehicle-pole, and Fig. 2 35 a detail view of the equalizer.

In the drawings, A represents the vehicle-pole, and B B' B² the whiffletrees, attached, respectively, to the long arms of levers C and C'. The lever C is fulcrumed on the end of a 40 rod or arm, D, placed parallel with the pole, its lower end being pivotally secured to a cross-bar, D', which is pivoted at its center to the pole and extends out on either side thereof.

45 The short arm or inner end of the lever C is pivotally secured to the end of a diagonally-arranged brace-rod, E, which extends beyond the cross-bar D', its upper end being adjacent to the side of the pole opposite that of the 50 lever C. To support and retain this brace E in place, a bar or brace, F, is placed parallel

with the inner end of the lever C and rigidly secured to the pole, its end being provided with a support or guide-plate, F', at the side of the pole below the lever C, for assisting in 55 supporting the same. To the opposite end of the cross-bar D' is pivoted an arm, D², extending forward and parallel with the arm D, its upper end forming a fulcrum for the lever C', which is shorter than the lever C, its short 60 arm being pivotally secured to the end of lever C and brace E.

G represents a laterally-arranged cross-bar centrally secured to the pole back of the cross-bar D'. The inner end of brace E is secured 65 to one end of this cross-bar G, and the end of an oppositely obliquely-arranged brace, H, is secured to the opposite end, the forward end of this brace H being secured to the pole at the pivotal point of the cross-bar D'. To more 70 effectively resist and equalize the stress on the brace and cross-pieces, I secure a parallel brace-strip, K, to the cross-pieces D' and G.

By the above arrangement and construction it will be noticed that a gradual and 75 regular distribution of the draft is secured, the location and arrangement of the several members being such as to avoid the usual results of all sudden jerks and vibrating movements of the power, and the back-pressure 80 obtained from the main levers obviates side draft and steadies the pole.

Having thus fully described my invention, what I claim as new, and desire to secure by 85 Letters Patent, is—

1. The draft - equalizer herein described, consisting of the levers C and C', the diagonal brace E, the cross-bars D' and G, the parallel fulcrum-arms D and D², and the braces H and K, substantially as described.

2. In a draft-equalizer, the combination, with the pole, of the levers C and C', the fulcrum-arms D and D², the cross-bar D', the diagonally-arranged brace E, the bar F, having plate F' on its end, the cross-bar G, and the 95 braces H and K, substantially as described.

In testimony whereof I affix my signature in presence of two witnesses.

ALFRED GILBERT BROWN.
